UNITED STATES PATENT OFFICE.

WILLIAM C. KASPER, OF LAKEWOOD, OHIO.

AWNING ATTACHMENT FOR AUTOMOBILES.

1,319,345.

Specification of Letters Patent. Patented Oct. 21, 1919.

Application filed December 16, 1918. Serial No. 266,961.

To all whom it may concern:

Be it known that I, WILLIAM C. KASPER, a citizen of the United States, residing at Lakewood, in the county of Cuyahoga and State of Ohio, have invented certain new and useful Improvements in Awning Attachments for Automobiles, of which the following is a specification.

This invention relates to attachments for automobiles, and has for its object to provide an awning or the like which is supported in position to shield or protect the wind-shield from snow and rain, and also to act as a shade from the sun when desired.

Various devices have heretofore been proposed for the purpose of preventing deposits of moisture or snow on wind-shields, which obscure the vision of the driver. The present invention is designed and intended as an improvement on these devices, and consists of an awning or the like which can be removed when its use is not necessary, and which can be quickly put in place when desired.

The invention may be embodied in various forms, one of which is illustrated in the accompanying drawings in which—

Figure 1 is a side elevation of part of an automobile provided with the attachment.

Fig. 2 is a plan of the attachment.

Fig. 3 is a detail in section showing the manner of attaching the device to the automobile top.

Fig. 4 is a detail of the support for the front end of the awning.

Referring specifically to the drawings, 6 indicates the automobile body, 7 the top thereof, 8 the windshield, 9 the radiator.

10 The attachment comprises an awning 10, which may be of any shape desired, but is conveniently triangular as shown. This awning has reinforcing strips 11, running from front to back, and at its rear corners it is provided with hooks 12, which are adapted to engage loops 13, conveniently fastened to the front bow 14 of the top 7.

15 The awning also has an upper flap 15, fastened along its rear edge, and of sufficient size to lap the joint between the rear end of the awning and the top. This flap may be fastened to the outside of the top as by snap fasteners 16.

The rear end of the awning is also pro-

vided on its under side with a gutter 17, 55 which consists of a piece of flexible material of sufficient width to extend across and hang below the joint between the awning and the top, and the rear edge of this gutter flap may be secured to the bow 14 as by snap 60 fasteners 18.

To support the front end of the awning, I substitute for the ordinary radiator cap, a cap 19 having a standard 20, the top of which has a collar 21, and an ornamental 65 nut 22 which screws on the standard. The front end of the awning has a loop 23, which fits over the top of the standard and rests on the collar 21.

In the use of the device, the rear end of 70 the awning is attached to the front of the top by the hooks 12, and the flap 15 and the gutter 17 are fastened in place. The loop 23 is engaged with the standard 20 and held by the nut 22. The awning will then extend in a substantially horizontal position over and in front of the windshield and will protect the same from the rain or snow. It will also be found very useful as a shade in driving toward the sun, as it will keep the 80 sun out of the eyes of the driver. When not in use the cap 19 and the standard 20 can be removed and the awning detached from the top and rolled up into small compass for storage under the seat or elsewhere. It 85 can be very quickly applied or detached, and can be made at much less cost than the glass supplemental rain shields heretofore known.

It may be remarked that the purpose of the gutter 17 is to catch any water which 90 may leak through between the top 7 and the flap 15, and such water will be drained out of ends of the gutter, beyond the windshield.

The invention is not limited to the form 95 shown and described, but may be embodied in various modified structures.

I claim:

1. The combination with an automobile and its top, of an awning detachably joined 100 to the front of the top and extending forwardly therefrom, and having a flap covering the joint and secured to the outside of the top, a gutter extending under the joint between the top and the awning, and means 105 to support the awning in extended position.

2. The combination with an automobile having a radiator at the front thereof, and

a top, of a triangular awning detachably fastened at its rear wide end to the front of the top and extending forwardly therefrom, and a standard mounted on the radiator and supporting the front apex end of the awning.

3. The combination with an automobile having a radiator at the front thereof, of a radiator cap provided with a standard, and an awning attached at its front end to said

standard and at its rear end to the automobile top.

In testimony whereof I do affix my signature in the presence of two witnesses.

WILLIAM C. KASPER.
